York, N. Y., a corporation of Delaware

Application October 15, 1932, Serial No. 637,902

9 Claims. (Cl. 132—36)

The present invention relates to permanent waving and more particularly to a permanent-waving heater for use in giving a croquignole or flat permanent wave.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:—

Figure 1 is a side elevation of the illustrative embodiment of the present invention;

Figure 2 is a vertical cross-section through the embodiment shown in Figure 1, with the left-hand portion of Figure 2 being taken on a medium vertical line, while the right-hand portion is taken to one side of said median line;

Figure 3 is a side elevation showing the inner side of one of the heating elements and its associated handle, with certain parts broken away;

Figure 4 is a detailed perspective view of a heat-distributing and lagging member in accordance with the present invention;

Figure 5 is a vertical longitudinal section through the device shown in Figure 4;

Figure 6 is a detailed perspective view of the casing for one of the heater elements;

Figure 7 is a detailed perspective view of the spring shown in Figure 2;

Figure 8 is a detailed longitudinal section of the heater element and insulation;

Figure 9 is a detailed side elevation of the handle shown in Figures 1 and 2;

Figure 10 is a perspective view of the insulation for the heater element of Figure 8; and

Figure 11 is a circuit diagram for the device shown in Figures 1 and 2.

The present invention has for its object the provision of a new and improved hair-waving apparatus which will produce an improved curl. A further object is the provision of an attachment for use with a permanent-waving heater for insuring uniform distribution of heat from the heater to the curl. Another object is the 55 provision of optionally usable means to vary

the time or intensity of heating required and thus make it possible for curls requiring different amounts of heat to be heated for the same length of time. Another object is the provision of means permitting a single type and size of heater to be used equally well on large and small 10 curls. Still another object is the provision of a heater of improved construction which is more durable, is formed of fewer parts, and can be manufactured more inexpensively than heaters now in use.

Referring now in detail to the illustrative embodiment of the invention as shown in the accompanying drawings, the lock of hair 1 to be curled is wound in the usual manner on a croquignole winding pin 2 of conventional construction. Pin 2 is removably mounted in open sockets 3 at the ends of clamping jaws 4 in the usual manner. Jaws 4 are also provided with the corrugated rubber inserts 5 which tightly clamp 15 the lock of hair and prevent the hair-waving lotion dripping on to the head of the person receiving the wave.

In accordance with the present invention, the heater comprises a pair of relatively long and narrow encased heater elements, each provided with a handle attached to the casing, and pivotally connected together and resiliently pressed towards each other. As embodied, the heater element comprises a length of insulated resistance wire 10 bent back and forth upon itself to form a relatively long, self-supporting element, with the wires insulated from each other, and held in position by the retaining bands 11 which are wrapped tightly around the shaped element. The 20 ends of the resistance wire 10 preferably extend from one of the longitudinal edges of the element in a position closely adjacent and parallel to each other.

Means are provided for insulating the heating element from its casing, and for this purpose a sheet of mica 13, or other insulating material, is provided with a pair of holes 14 positioned to correspond to the ends 12 of the resistance wire. These holes 14 are preferably positioned centrally 25 of the sheet 13 so that the insulating sheet may be wrapped around the heating element after it has been shaped.

The ends 12 of the resistance wire 10 are connected to connectors 15, as by soldering, and 30 these connectors are in turn secured to flexible conductors 16 and 16' through which electric current is supplied to the heater elements.

Figure 11 of the drawings is a circuit diagram showing the manner in which a pair of heating 35

elements are connected together in series by conductor 16', and by conductors 16 to the source of current supply.

The casing for the heater elements preferably 5 comprises a single sheet of aluminum, or other material, bent upon itself to completely enclose the heater element and also to provide projecting ears by which it may be attached to its handle. As embodied, and as shown in detail in Figure 6, 10 this sheet is so shaped and bent upon itself as to form a pair of similarly curved, long and narrow side walls 20, spaced from each other and connected together along their bottom edges by a sharply curved portion 21 of the sheet. The 15 upper edges 22 of the curved side walls are adapted to fit tightly against each other when the casing is assembled. This sheet of material is also provided with integral end walls 23 adapted to close the space between and at the ends of 20 the side walls 20. Ear 24 projects from one of the side walls and a smaller ear 25 projects from the other and is bent to a position substantially parallel to that of ear 24. Ears 24 and 25 are apertured at 26 to receive a rivet by which they are 25 held to their handle, as will be later described, while ear 24 is also provided with a pair of inwardly-extending lugs 27 by which one heater may be pivotally mounted upon another.

Each of the heaters is provided with a handle 30, formed of material which is preferably both a heat and electrical insulator. Handle 30 is provided with an aperture 31 to coincide with apertures 26 in the ears 24 and 25, and is also provided with a pair of channels 32 to receive the flexible 30 conductors 16, 16', connected to the ends 12 of resistance wire 10. Channels 32 communicate with larger channels 33 in which are seated the connectors 15, serving to prevent transmission of strain from the flexible conductor 16 or 16' to the 35 resistance wire ends 12, inasmuch as connectors 15 are of larger size than the channels 32.

In the assembly of the heater, the heater element, provided with its encasing insulating sheet 13 properly folded about it, is positioned within 40 the space between side walls 20 of the casing, and this assembly may be easily accomplished by 45 springing the side walls slightly apart while the element is inverted. Handle 30 is then positioned between ears 24 and 25, and connectors 15 and 50 conductors 16, 16' are properly arranged within channels 32 and 33. A thin strip of mica, or other flexible insulating material 35 is then positioned between handle 30 and ear 24, to prevent 55 contact of connectors 15 with the metal of the casing, and the side walls 20 are then pressed together until ears 24 and 25 are tight against opposite sides of the handle 30.

With the parts in this position, a single rivet 34 is passed through aligned apertures 26 and 31, and through an apertured reinforcing member 60 36 of relatively large size. The rivet may then be spun out to secure and firmly hold the parts in this position.

By constructing the casing for the heating element of a single piece, and by preshaping the heating element before inserting it in the casing, a very compact and strong assembly is produced, and the tendency of ears 24 and 25 to bend, as the heating element is moved by its handle 30, 65 is greatly reduced, while reinforcing piece 36 further increases the strength of this assembly permitting the use of very light weight material with a consequent reduction in the weight to be supported on the patient's head.

70 A pair of the heaters are adapted to be pivotally

connected together to form the heater clamp which surrounds the lock of hair wound on mandrel 2, and means are also provided for resiliently pressing the heater elements towards each other and into engagement with the wound hair. For effecting this pivotal connection, each of the ears 24 is provided with a pair of integral lugs 27, extending away from handle 30 and projecting from opposite edges of the ear 24.

75 These lugs 27 are apertured, as at 28, and the apertures of the four lugs on the pair of heaters are held in alignment while the pivot pin 37 is passed through them to pivotally mount one heater upon its mate.

For pressing the heater elements towards each other, a spring 38 is coiled about pivot pin 37. As shown in Figure 7, this spring comprises a pair of axially aligned helical coils 39 connected together at their adjacent ends by a U-shaped portion 40 of the spring wire which is adapted to 20 lie against one of the ears 24. Near the outer ends of the coils the spring wire is bent to form a relatively wide loop 41 which bears against the other ear 24 and also serves as a stop limiting the movement of handles 30 towards each 25 other. This limit for the movement of the handles prevents sharp bending of the flexible conductor 16', connecting the coils of the two heating elements together, thereby increasing the 30 life of the heater. Spring 38 is preferably quite strong and gives sufficient pressure to tightly press the heating elements into contact with the curl with the necessary pressure.

In accordance with the present invention, and 35 as shown in detail in Figures 4 and 5 of the drawings, a heat-distributing or lagging member is provided for uniformly distributing the heat supplied from the heating elements to the curl, as well as for reducing the intensity of the heat so 40 supplied. By means of this device, those curls 45 which do not require as intense or as long a period of heating may be treated for the same length of time as other curls, facilitating the work of the operator, and preventing injury to the hair such as may occur through incorrect and confused 45 operation of the switches.

As embodied, the heat-distributing member provides an air space between the curl to be waved and the heating elements, the air space serving to prevent uneven heating of the curl and also reducing the intensity of the heat transmitted to the curl by the heater. This member preferably 50 comprises a parti-cylindrical shell 45 of a length substantially the same as that of the winding pin 2, and slightly longer than the length of the 55 wound curl to be waved. This parti-cylindrical shell is also somewhat larger than the diameter of the wound curl and is formed from a thin sheet of resilient metal. Shell 45 is secured to a second and inner shell 46, of a diameter slightly 60 less than that of shell 45, and of substantially the same length. Shell 46 is also parti-cylindrical and along its edges the metal is folded outwardly and back upon itself a short distance to provide 65 channels 47 in which are received and tightly held the longitudinal edges of shell 45, thus securing the inner shell to the outer shell and forming a crescent-shaped member having open ends and an air space between its component shell.

70 Shells 45 and 46 are both preferably resilient and the structure as a whole may be bent to vary its internal and external diameter and thus conform it to the size of curl with which it is to be used.

75 In waving hair with the illustrated embodiment 75

of the present invention, a lock of hair is wound on the winding pin on mandrel 2 and is clamped between the rubber jaws 5 in the usual manner. When properly wound, a pad comprising an absorbent and moisture-retaining layer 50, such as felt, saturated with hair-waving lotion, is positioned around the wound curl, and this may be covered with a layer of thin metal foil 51.

The heat-distributing member is then pressed

10 over the curl and resiliently presses the lotion-saturated pad 50 into intimate contact with the curl to be waved. The heater clamps are then opened by pressing the handle portions 30 together and the heaters are clamped on to the heat-distributing members with the inner side walls 20 of the heater in contact with the outer shell 45 of the heat-distributing member. Spring 38 resiliently holds the heaters in contact with the shell 45 and the curl is heated for the desired 15 length of time with the parts in this position.

Where all of the curls to be waved are substantially the same size and require substantially the same period of heating, the heat-distributing members may be placed over each of the curls.

20 However, it often happens that certain curls require longer periods of heating than others, and when this is the case, the heat-distributing members are used with those curls which would normally require a shorter period of heating, said 25 members serving to reduce the intensity of the heat so that all of the heaters may be switched on and off simultaneously, thereby reducing the chance that the operator might mistakenly turn the switches off at the wrong time.

30 The invention in its broader aspects is not limited to the specific mechanism shown and described but departures may be made therefrom within the scope of the accompanying claims without departing from the principles of the invention and without sacrificing its chief advantages.

40 What we claim is:—

1. As a new article of manufacture for use in hair waving, a pair of inter-connected parti-cylindrical members, spaced from each other and joined together along both their longitudinal 45 edges to form a spacer.

2. As a new article of manufacture for use in hair waving, a parti-cylindrical spacer formed of resilient metal, a second and slightly larger parti-

cylindrical sleeve of resilient metal overlying said first sleeve and joined thereto along its longitudinal edges.

3. A hair waving device including in combination a mandrel on which the hair is wound, a heater to surround and heat the hair wound on said mandrel and a heat distributing cushion adapted to be positioned between the hair and heater.

4. A hair waving device including in combination a mandrel on which the hair is wound, a heater to surround and heat the hair wound on said mandrel and a flexible metallic cushion positioned between said hair and heater and providing an air space therebetween.

5. A hair waving device including in combination a mandrel on which the hair is wound, a heater to surround and heat the hair wound on said mandrel and a resilient heat distributing cushion to be positioned around said wound hair and be held thereagainst by said heater.

6. A hair waving device including in combination a mandrel on which the hair is wound, a heater to surround and heat the hair wound on said mandrel and a pair of inter-connected parti-cylindrical metallic sheets forming a cushion and serving to clamp said hair and space the heater therefrom.

7. A hair waving device including in combination a mandrel on which the hair is wound, a heater to surround and heat the hair wound on said mandrel and a crescent-shaped heat distributing cushion to lie between said hair and heater.

8. As a new article of manufacture for use in permanent waving of human hair by means of an external heater, said article comprising a spacer cushion of substantially crescent shape section and adapted to be positioned around a wound curl and between the curl and the heater.

9. As a new article of manufacture for use in permanent waving of human hair, a resilient spacing member having smooth outer and inner surfaces and being of sufficient thickness to delay and distribute the flow of heat through it from one surface to the other.
